UNITED STATES PATENT OFFICE.

LEO MARDER, OF BROOKLYN, NEW YORK.

DESIGN FOR A HAND MIRROR.

Application filed March 31, 1922. Serial No. 1,472. Term of patent 3½ years.

To all whom it may concern:

Be it known that I, LEO MARDER, a citizen of the United States, residing in the borough of Brooklyn, county of Kings, city and State of New York, have invented a new, original, and ornamental Design for Hand Mirrors, of which the following is a specification, reference being had to the accompanying drawing, forming part thereof.

Fig. 1, is a front elevation; Fig. 2, is a rear elevation; and Fig. 3, is a transverse section on plane of line 3—3, Fig. 1, of a hand mirror, showing my new design.

I claim: The ornamental design for a hand mirror, as shown.

LEO MARDER.
